US0D1019144S

(12) **United States Design Patent** (10) **Patent No.:** **US D1,019,144 S**
Seiders et al. (45) **Date of Patent:** **** Mar. 26, 2024**

(54) **BAG**(71) Applicant: **YETI Coolers, LLC**, Austin, TX (US)(72) Inventors: **Roy Joseph Seiders**, Austin, TX (US);
Dustin Bullock, Austin, TX (US)(73) Assignee: **YETI Coolers, LLC**, Austin, TX (US)(***) Term: **15 Years**(21) Appl. No.: **29/769,322**(22) Filed: **Feb. 4, 2021****Related U.S. Application Data**

(63) Continuation of application No. 29/705,665, filed on Sep. 13, 2019, now Pat. No. Des. 920,678, which is a continuation of application No. 29/648,869, filed on May 24, 2018, now Pat. No. Des. 861,338, which is a continuation of application No. 29/595,100, filed on Feb. 24, 2017, now Pat. No. Des. 822,987.

(51) **LOC (14) Cl.** ..... **03-01**(52) **U.S. Cl.**USPC ..... **D3/246**(58) **Field of Classification Search**

USPC D3/232, 245, 246, 318; D7/607

See application file for complete search history.

United States District Court Western District of Texas Austin Division, "Defendants RTIC Outdoors, LLC's and Corporate Support & Fulfillment, LLC's Invalidity Contentions", *YETI Coolers, LLC v. RTIC Outdoors, LLC and Corporate Support & Fulfillment, LLC*, Case No. 1:21-cv-00214, Jury Trial Demanded, filed Jan. 17, 2022, 3173 pages.

(Continued)

Primary Examiner — Jennifer L Watkins(74) *Attorney, Agent, or Firm* — Banner & Witcoff, Ltd.**CLAIM**

The ornamental design for a bag, as shown and described.

DESCRIPTION

FIG. 1 is a top, front, right perspective view of a bag showing our new design;

FIG. 2 is a right side view thereof; and,

FIG. 3 is a left side view thereof.

The evenly dashed and dotted broken lines on claimed surfaces depict stitching and form no part of the claim. The surfaces surrounding the stitching are claimed. The dot dash dot line depicts the claim boundary and forms no part of the claim.

1 Claim, 2 Drawing Sheets# US D1,019,144 S
